UNITED STATES PATENT OFFICE.

CONRAD M. PITEL, OF MERIDEN, CONNECTICUT.

DROP-LIGHT.

No. 913,976.

Specification of Letters Patent.

Patented March 2, 1909.

Application filed March 30, 1908. Serial No. 424,256.

To all whom it may concern:

Be it known that I, CONRAD M. PITEL, a citizen of the United States, residing at Meriden, in the county of New Haven and State 5 of Connecticut, have invented a new and useful Improvement in Drop-Lights; and I do hereby declare the following, when taken in connection with the accompanying drawings and the numerals of reference marked there- 10 on, to be a full, clear, and exact description of the same, and which said drawings constitute part of this specification, and repre- sent, in—

Figure 1 a side view partially in section of 15 a suspension lamp fixture converted for use with gas or electricity. Fig. 2 a sectional view illustrating the adaptation of my invention for use with another form of burner.

This invention relates to an improvement 20 in drop lights, the object being to adapt a hanging oil lamp fixture of the suspension type for use with gas or electricity; and the invention consists in the construction herein- after described and particularly recited in 25 the claims.

In illustrating my invention I have shown it in connection with the parts of a hanging oil lamp of usual construction which includes a shade-holding ring 2 which supports the 30 shade 3 and to which a harp 4 carrying the font or font shell 5 is connected, the shade ring being suspended by chains 6 to a ring 7 which in turn is suspended by chains 8 with the suspension device 9 which may be of any 35 approved construction adapted to permit the lamp to be raised or lowered. This suspen- sion device is hung upon a hook 10 formed in- tegral with the plug cap 11 which is attached to a nipple 12 of the gas pipe in the usual 40 manner. As usual in this class of lamps the shade is provided with a metal crown 13.

As thus far described the parts are of usual construction and may be of any approved design.

Secured to the crown 13 and supported by 45 a bracket 15 attached to the inner face of the crown is a hollow arm 16, this arm projecting radially outward from the crown and pro- vided at its outer end with a nipple 17 and at 50 its inner end with a goose neck 18 to which an inverted mantle burner 19 of approved construction is attached, the burner being suspended centrally within the shade 3. En- tered into the plug cap 11 and so as to con- 55 nect with the gas pipe 12 is an outwardly ex-

tending pipe arm 20 having a valve 21 oper- ated by a key 22 which may be turned by chains or cords 23, 24, extending downward to convenient points. Coupled with the outer end of the pipe arm 20 and the nipple 60 17 is a flexible tube 25 through which gas may flow, and the pipe arm 20 will be of suffi- cient length so as to carry the flexible connec- 65 tion 25 so far to one side of the shade that it is not liable to be affected by heat from the burner.

Instead of employing an inverted mantle burner as above described, an upright burner may be employed; in which case instead of having a goose neck 18 the hollow arm 16 70 70 may be tapped on the underside of its inner end for the attachment of a gas pipe 26 which extends down to the bottom of an up- right burner 27 which may be of the Wels- bach, Argand or other style of burner, this 75 burner being additionally supported by a dummy pipe 28 extending upward into en- gagement with the crown 13 at a point op- posite the hollow arm 16.

It is apparent without further illustration 80 that instead of using gas, electric lights may be suspended in the same way by carrying the wires out upon an arm and having a long connection between the pipe arm and the hollow arm. It will thus be seen that a 85 hanging oil lamp of usual construction may have the harp and font removed and the crown replaced by a crown constructed in accordance with my invention and the rest of the device used in its usual way, thus pro- 90 viding a drop light fixture for use with gas or electricity.

I claim:—

1. A drop light comprising a shade ring, a suspension device for supporting the same, 95 a shade and a metal crown therefor, a hollow arm connected with said crown, a burner supported by said hollow arm, a pipe arm above the fixture, and a flexible conductor connecting the pipe arm and the hollow arm, 100 substantially as described.

2. The combination with a shade ring, a suspension device therefor, a shade support- ed by the shade ring, a metal crown on said shade, a hollow arm connected with said 105 crown and projecting radially outward there- from, a nipple at the outer end of said hollow arm, a burner supported by said arm and extending into said shade, a pipe arm pro- jecting outward beyond the suspension de- 110

vice, and a flexible connection between the pipe arm and the hollow arm, substantially as described.

3. In a drop light, the combination with
5 the suspension device, a shade ring supported thereby, a shade, a crown thereon, a hollow arm connected with said crown and projecting radially outward therefrom, a nipple at the outer end of said hollow arm,
10 a goose neck connected with said hollow arm and carrying a burner which stands within said shade, a pipe arm projecting outward

above and beyond the suspension device, and a flexible connection between the pipe arm and the hollow arm, substantially as 15 described.

In testimony whereof, I have signed this specification in the presence of two subscribing witnesses.

CONRAD M. PITEL.
